DOLL CRADLE

Frank Soodhalter and Paul J. Mochel,
Los Angeles, Calif.

Application December 5, 1949, Serial No. 6,424

Term of patent 3½ years

(Cl. D34—15)

To all whom it may concern:

Be it known that we, Frank Soodhalter and Paul J. Mochel, both citizens of the United States, residing at Los Angeles, in the county of Los Angeles and State of California, have invented a new, original, and ornamental Design for Doll Cradle, of which the following is a specification, reference being had to the accompanying drawings, forming part thereof.

Fig. 1 is a top plan view of a doll cradle, showing our new design;

Fig. 2 is a side elevational view;

Fig. 3 is an end elevational view;

Fig. 4 is a sectional view thereof on lines 4—4 of Fig. 2; and

Fig. 5 is also a sectional view and taken on lines 5—5 of Fig. 3.

We claim:

The ornamental design for a doll cradle, as shown.

FRANK SOODHALTER.
PAUL J. MOCHEL.
